UNITED STATES PATENT OFFICE

2,553,892

SAFETY SWITCH FOR MOTOR VEHICLES

Ward V. Brugger, Nichols, Wis.

Application November 26, 1948, Serial No. 62,007

2 Claims. (Cl. 200—162)

1

The present invention relates to new and useful improvements in electrical switches and more particularly to a safety switch for use with automobiles and other motor vehicles and designed for disconnecting the electrical circuit of the vehicle at a point between the battery and the starter switch.

An important object of the invention is to provide a safety switch of this character whereby the battery may be disconnected to prevent leakage of the current when the vehicle is idle, as well as to prevent the hazard of fire in case of a short circuit in the electric system.

A further object of the invention is to provide a safety switch of this character which may be easily and quickly mounted in a suitable position to a part of a motor vehicle and which at the same time is simple and practical in construction, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the switch;

Figure 2 is a vertical sectional view;

Figure 3 is a vertical transverse sectional view taken on the line 3—3 of Figure 2;

Figure 4 is a fragmentary vertical sectional view taken on a line 4—4 of Figure 2; and

Figure 5 is an enlarged fragmentary sectional view of the locking connection for the pivot pin for the switch.

Referring now to the drawing in detail wherein for the purpose of illustration I have disclosed a preferred embodiment of the invention, the numeral 5 designates an attaching base or plate of insulation material and on which a switch housing 6 is secured by flanges 7 at the lower edge of the housing secured to the base 5 by screws or the like 8. The top of the housing 6 is curved as shown at 9 and formed with a slot 10.

Terminals 11 and 12 extend through the base 5, the upper or inner end of terminal 11 having a head 13 positioned in the bottom of a channel-shaped contact 14 having inwardly and downwardly curved upper edges to form a pair of spaced apart resilient contact plates 15.

A bolt or pin 16 extends transversely through the sides of the contact 14 and through the lower ends of contact plates 15, one end of the pin

2

16 having a head 17 and the other end of the pin having a nut 18 threaded thereon. A coil spring 19 is positioned between head 17 and the contact plate 15 at the adjacent side of the contact 14 and a similar coil spring 20 is positioned between nut 18 and the other contact plate 15, the springs 19 and 20 urging the contact plates 15 toward each other.

The inner or upper end of terminal 12 is also formed with a head 21 positioned in the bottom of a channel-shaped bracket 22 having opposed resilient side walls 23 and in which a pivot pin or bolt 24 is positioned transversely thereof.

The bolt or pin 24 is also formed with a head 25 at one end and a nut 26 threaded on its opposite end and coil springs 27 and 27a are positioned on the opposite ends of the pin or bolt 24 to bear against the resilient side 23 of the bracket to urge the same inwardly.

20 The heads 17 and 25 of each of the pins or bolts 16 and 24 are formed with a notch 28 in which the adjacent end of its associated coil spring 19 or 27, as the case may be, is engaged as shown in Figure 5 of the drawing to lock the pin or bolt from turning movement.

An L-shaped switch lever is designated generally at 29 and includes an upstanding handle 30 preferably of light gauge metal and to the lower end of which an inverted channel member 31 is welded or otherwise suitably secured. An insulation plate 32 is riveted in the channel member 31 and a channel-shaped conductor member 33 of copper or other suitable material is riveted or otherwise suitably secured to the lower edge of insulation plate 32. One end of the conductor member 33 is pivoted on the pin 24 between the resilient sides 23 of bracket 22 and the other end of conductor member 33 is raised and lowered between the resilient contact plates 15.

45 Accordingly by connecting the terminals 11 and 12 in a battery cable (not shown) between a battery and a starter switch of a motor vehicle, and swinging handle 30 back and forth the knife or switch blade 33 will be moved into and out of engagement with contact plates 15 to open and close the circuit.

The handle 30 is enclosed in a flexible dust and moisture-proof cover 34 covering slot 10 and secured to housing 6 by a rigid frame 35.

50 In view of the foregoing description taken in conjunction with the accompanying drawings it is believed that a clear understanding of the device will be quite apparent to those skilled in

this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A switch comprising a base of insulation material, a housing on top of the base having a slot, a pair of terminals extending upwardly through the base into the housing, a pair of channel members secured to the upper ends of the terminals in the housing, one of said channel members comprising a conductor and the other channel member comprising a contact, an L-shaped lever having an inverted channel at its lower edge, an insulation strip secured in the inverted channel, and a channel conductor secured to the lower edge of the insulation strip and pivoted adjacent one end to said first named channel conductor and movable into and out of engagement with the contact.

2. A switch comprising a base of insulation material, a housing on top of the base having a slot, a pair of terminals extending upwardly through the base into the housing, a pair of channel members secured to the upper ends of the terminals in the housing, one of said channel members comprising a conductor and the other channel member comprising a contact, an L-shaped lever having an inverted channel at its lower edge, an insulation strip secured in the

inverted channel, a channel conductor secured to the lower edge of the insulation strip and pivoted adjacent one end to said first named channelled conductor, and said channelled contact comprising inwardly and downwardly curved opposed resilient flanges united with the sides of the contact and positioned inwardly and spaced therefrom to receive the second named channel conductor, said flanges and said sides of the contact having aligned openings, a pin slidable in said openings, a pair of coil springs on the pin adjacent its ends and with the inner ends of the springs bearing against an adjacent flange and said springs being freely positioned in the openings at the sides of the contact, and means at the ends of the pin holding the springs under tension and including means for adjusting the tension of the springs.

WARD V. BRUGGER.
